Primary Examiner—Elizabeth A. Albert*Assistant Examiner*—Karen E Eldridge Powers(74) *Attorney, Agent, or Firm*—Christensen O'Connor Johnson Kindness PLLC(57) **CLAIM**

The ornamental design for a pen, as shown and described.

DESCRIPTION

FIG. 1 is a perspective view of a pen showing our new design;

FIG. 2 is an exploded perspective view of the pen shown in FIG. 1;

FIG. 3 is a perspective view of the pen shown in FIG. 1 with the pen cap removed and placed on the opposite end of the pen;

FIG. 4 is a top plan view of the pen shown in FIG. 1;

FIG. 5 is a bottom plan view thereof; and,

FIG. 6 is a side elevation view thereof.

The stippled shading shown on a portion of the pen represents a surface texture.
